Primary Examiner — Cynthia R Underwood(74) *Attorney, Agent, or Firm* — QuickPatents; Kevin Prince(57) **CLAIM**

The ornamental design for a hook, as shown and described.

DESCRIPTION

FIG. 1 is a perspective view of a hook, showing my new design with a sliding clasp in a closed position;

FIG. 2 is a front elevational view of FIG. 1;

FIG. 3 is a rear elevational view thereof, illustrated with the sliding clasp in an open position;

FIG. 4 is a left-side elevational view of FIG. 1;

FIG. 5 is a right-side elevational view of FIG. 1;

FIG. 6 is a top plan view of FIG. 1;

FIG. 7 is a bottom plan view of FIG. 1; and,

FIG. 8 is a front perspective view thereof, illustrated with the sliding clasp in the open position.

The broken lines showing a sliding clasp in the figures depict environmental matter and form no part of the claimed design.
